UNITED STATES PATENT OFFICE.

EDUARD HEBER, OF NEW YORK, N. Y.

PROCESS FOR CLARIFYING AND DEODORIZING OIL-OF-WOOD TURPENTINE.

No. 830,069.

Specification of Letters Patent.

Patented Sept. 4, 1906.

Application filed May 26, 1906. Serial No. 318,832.

To all whom it may concern:

Be it known that I, EDUARD HEBER, doctor of philosophy, a subject of the German Emperor, residing at No. 107 Henry street, 5 in the city of New York, borough of Brooklyn, county of Kings, and State of New York, have invented a certain new and useful Process for Clarifying and Deodorizing Oil-of-Wood Turpentine, of which the following is a 10 specification.

This invention relates to the process for clarifying and deodorizing oil-of-wood turpentine, and has for its object to render the process more expeditious and considerably 15 cheaper.

Oil-of-wood turpentine in the United States is obtained from the roots and trunks of the dead long-leaf pine (*Pinus maritima*) and is ordinarily obtained from the light 20 wood or heart from which the outer covering of sap-wood has been rotted away. It is ordinarily obtained by heating the wood in a suitable retort in which the oil-of-wood turpentine is vaporized, and afterward it is 25 condensed and collected. As thus obtained it consists not only of oil-of-wood turpentine, but also coloring-matter, odoriferous matter, and tarry substances.

My process of purification is as follows: I 30 first remove the tarry constituents by distillation over lime. This is accomplished by mixing the crude oil-of-wood turpentine thoroughly with from one to two per cent. of lime mixed with water and then distilling by 35 means of steam. The oil-of-wood turpentine is then mechanically separated from the water, and as thus obtained it is in a partially purified and clarified condition, but still contains considerable coloring and odoriferous 40 matter. Then I add to the oil-of-wood turpentine a sufficient quantity of ordinary soap solution to dissolve or emulsify the oil and then treat this oil-of-wood-turpentine solution or emulsion with potassium permanganate, sodium permanganate, or calcium 45 permanganate mixed with sulfuric acid. Soap solution possesses the property of dissolving or emulsifying oil-of-wood turpentine, the result being that when the potassium 50 permanganate and sulfuric acid are mingled with the emulsified oil-of-wood turpentine these chemicals come into contact with all the minute particles thereof and practically with all the particles at once. It is not possible to accomplish the same result with an agitator alone, for the reason that the oil-of- 55

wood turpentine, which must be mingled with water, cannot by the best-known agitator be broken up into particles sufficiently small to enable the operator to accomplish 60 the same result. As a result of the emulsification the permanganate is in a position to readily destroy only the odoriferous matter and the coloring-matter of the oil-of-wood turpentine, which, as I have discovered, are 65 more easily oxidized or attacked than the oil-of-wood turpentine, and this result is accomplished without the destruction of any appreciable part of the pure oil-of-wood turpentine. I am thus able to accomplish the desired 70 result with a minimum amount of chemicals and with the destruction of a minimum amount of oil-of-wood turpentine, and I am also able to more thoroughly deodorize and clarify my product.

An example of my process is as follows: I place one hundred pounds of oil-of-wood turpentine from which the tarry constituents have been removed by distillation over lime, as above described, in an ordinary iron still 80 or retort which is provided with a suitable agitator. To this I add a sufficient quantity of ten-per-cent. soap solution to thoroughly dissolve or emulsify the oil-of-wood turpentine. Into this emulsion I flow slowly a five-per cent. permanganate solution holding three to five pounds of potassium permanganate and four to six pounds of concentrated sulfuric acid of 66° Baumé in solution while the contents of the still is being constantly 90 agitated or stirred. The agitation is continued until the permanganate solution introduced into the still has completely lost its color, after which by the addition of calcium chlorid or zinc sulfate the soap solution is 95 precipitated as indissoluble calcium or zinc soap. The oil-of-wood turpentine is then distilled off by means of steam or high-pressure steam, after which the oil-of-wood turpentine is mechanically separated from the 100 water and forms a colorless liquid having an agreeable odor resembling that of essential oils and very similar to gum-turpentine. The treatment with chromic acid and sulfuric acid may be effected in the same manner, the same proportions and the same strength of solution being used as when the treatment is with potassium permanganate, described above, the stirring of the mixture being continued until the change of color of the 105 chromic acid indicates that the reaction has been completed. If chromic acid is em-

ployed in the shape of its salts, about six to nine pounds of potassium bichromate (or a corresponding quantity of sodium bichromate) should be used for each one hundred 5 pounds of oil-of-wood turpentine, which has been subjected to a preliminary purification by distillation over lime, and then dissolved or emulsified by a soap solution, as above described. These six to nine pounds of bichromate are converted into a five-per-cent. aqueous solution, and four to seven pounds of concentrated sulfuric acid of 66° Baumé are added to the same. The solution thus prepared is caused to flow slowly into the still, 10 as above described, and the operation is completed exactly as described for chromic acid.

Having thus described my process, what I claim is—

1. The process of clarifying and deodorizing oil-of-wood turpentine, which consists of first emulsifying the oil-of-wood turpentine with a soap solution, and then adding to the same chemicals, which attack and destroy the coloring-matter and odoriferous matter mingled therewith.

2. The process of clarifying and deodorizing oil-of-wood turpentine, which consists of emulsifying the oil-of-wood turpentine with a soap solution, adding thereto chemicals which will attack and oxidize the coloring-matter and odoriferous matter mingled therewith, precipitating the soap solution, and

separating the oil-of-wood turpentine therefrom.

3. The process of clarifying and deodorizing oil-of-wood turpentine, which consists in first removing the tarry substances by distillation over lime, emulsifying the oil-of-wood turpentine, adding thereto chemicals which will attack and oxidize the odoriferous matter and coloring-matter mingled therewith, precipitating the soap solution and separating the oil-of-wood turpentine therefrom.

4. The process of deodorizing and clarifying oil-of-wood turpentine, which consists of first removing the tarry substances by distillation over lime, second, emulsifying the resultant product with a soap solution, third, adding to the emulsion chemicals which will attack and oxidize or destroy the odoriferous matter and coloring-matter which are mingled with the oil-of-wood turpentine, fourth, precipitating the soap solution, and fifth, distilling off the oil-of-wood turpentine by means of steam, condensing the same, and separating the oil-of-wood turpentine from the water by any mechanical means.

Signed at New York city, in the county of New York and State of New York, this 21st day of May, A. D. 1906.

EDUARD HEBER.
